UNITED STATES PATENT OFFICE

ROBERT T. WILLIAMS, OF QUINCY, ILLINOIS, ASSIGNOR TO H. M. SHEER COMPANY, OF QUINCY, ILLINOIS, A CORPORATION OF ILLINOIS

BROODER

Application filed May 27, 1927. Serial No. 194,788.

This invention relates to an improvement in brooders.

The object of the invention is to provide for supporting a canopy for brooders in such a manner as to permit of its being raised or lowered and adjusted to its proper positions relative to the heater which is placed beneath or within the canopy. The heater is preferably a coal burning stove, or of some similar form for burning solid fuel. It is also a feature of this invention that the canopy is supported upon a base entirely independent of the heater, and this permits of its being adjusted to various positions relative to the heater. The heater itself may in fact be supported upon the same base which carries the canopy, thereby rigidly anchoring the canopy.

Another object of the invention is to allow the canopy to be turned upon its support so as to gain access, through an opening or door in the canopy, to any of the parts of the heater or stove, as the grate, dampers, thermostatic controls, etc., for adjusting and regulating the same.

Still another object of the invention is the provision of an opening in the top of the canopy for allowing a circulation of air from beneath the canopy and around the heater or stove. This carries off the foul air and gases which normally accumulate in the top of the canopy, and also provides for heating the brooder house by circulating the heated air around through the same while not detracting from the heat within the canopy. The thermostatic control normally employed for these brooder heaters is located under the canopy where also the chickens congregate, and consequently will maintain the proper heat at that point.

The heater is seated upon a base from which the channel bar support extends upwardly and is connected therewith, and a bearing-ring is adjustably supported upon the channel bar support near the upper end of the stove, and receives a bearing support carrying a canopy, and which permits of the canopy being turned about on the bearing-ring so as to position the door which is formed in the canopy in proper relation to

the parts of the stove as to gain easy access thereto for regulating the dampers and feeding fuel into the stove. The door in the canopy also permits of removing the canopy entirely from the bearing-ring by merely opening the door and lifting the canopy off, the opening in the side of the canopy permitting the lifting of the canopy off around the pipe.

In the accompanying drawings:

Fig. 1 is a side elevation partly in section of the complete invention;

Fig. 2 is a perspective view of the base, bearing ring and channel bearing support; and

Fig. 3 is a top plan view of the brooder, parts of the canopy being broken away.

The numeral 1 represents the base having supporting lugs 2 extending upwardly therefrom for receiving and supporting the base of the stove or other form of heater 3. The base 1 may be movable over the floor of the brooder house, or otherwise, but the phrase "movable relative to the enclosure for the brooder" occurring in the claims, refers merely to the movable character of the base and brooder as distinguished from a support for the canopy fixed to the ground or to a fixed floor of the brooder house. The form of stove as here illustrated is of the coal-burning type, but it may be of any preferred construction for burning solid or other fuel. The stove 3 is provided with a feed-door 4 in the top thereof, as shown in Fig. 3, of a diameter substantially coextensive with the diameter of the top of the stove, thus allowing a large area for the reception of a coal-scuttle used in placing fuel in the stove. The stove-pipe 5 also extends upwardly from the top of the stove 3.

A bracket 6 is formed at the back of the base 1, and a channel bar support 7 extends over this bracket and is secured thereto by suitable bolts 8.

The channel bar support 7 extends upwardly behind the stove 3, and is provided with a plurality of small holes 9 therein near its upper end and intermediate portions for receiving a pin 10 formed on a bearing-ring 11 when the ring is slipped over the channel bar support. Guide-lugs 12 are also formed

on the bearing ring 11, as clearly shown in Fig. 2, in order to guide the passage of the ring from the channel-bar support and hold it in its proper position thereon when released with the pin 10 extending into one of the holes 9. The holes 9 permit of the ring being adjusted up and down relative to the channel bar support.

A bearing support 13 is in the form shown in Fig. 3, and is circular in shape corresponding to the shape of the bearing-ring 11, but does not extend entirely about said ring, being open on one side as shown in Fig. 3. This bearing support 13 is provided with a 15 downturned flange 14 to which a canopy 15 is secured by any suitable fastening means, as for instance bolts 16. A door 17 is hinged to the canopy 15 by the hinges 18, and the opposite side of the door may be connected 20 with the corresponding edge of the canopy by any suitable latch construction. Since the bearing support 13 extends only part way about the bearing-ring 11, and the remainder is closed by the door 17, which is not only 25 closed, but upon the release of the latch it may be opened to allow the removal of the canopy from the stove and its support, the opening between the ends of the bearing support passing about the stove-pipe 5. The 30 door 17 may also be opened to gain access to the feed-door 4 for supplying fuel to the stove or for gaining access to any other part of the stove, as, for instance, the regulating of the drafts, etc., merely upon the turning 35 of the canopy about its bearing-ring. Any of the terms "bearing support", or "bearing ring" or "bearing means" which may appear in the claims are intended to mean a journal for the canopy about an approximately vertical axis and about the upwardly extending body of the stove or heater, as distinguished 40 from a pivotal support for the canopy about a horizontal axis, as shown for instance in the U. S. patent to Clemmensen, No. 1,637,036, 45 July 26, 1927.

The bearing support 13 which is connected with the canopy 15 is seated upon the bearing-ring 11, which forms a support for the canopy independently of the stove, and the entire structure is supported upon the base 1 forming a secure support therefor being anchored by the stove resting thereon. The canopy may thus be adjusted up and down along the channel-bar support 7 merely by removing the canopy from the bearing-ring 11 and adjusting this ring by turning the front side thereof upward which moves the pin 10 out of its receptive hole 9 and allows the ring to slide up and down along the channel-bar support 7 until the proper hole is reached, this movement being regulated by the guide lugs 12 which keep the ring in proper relation to the support, and the pin 10 entering the proper hole 9 will thus adjustably support the canopy in its proper re-

lation to the stove and ground or floor upon which it is seated. As shown in Figs. 1 and 3, a space 19 may be provided between the bearing ring 11 which supports the canopy and the edges of the stove to permit a circulation of air through the top of the stove from within the brooder chamber beneath the canopy.

A simple and novel form of supporting means is thus provided for the canopy of a stove which will allow the canopy to be adjusted relative to its supporting base and the burner which is also carried thereby, and in this way the support for the canopy is entirely free from, and independent of, the burner or stove. This also allows the stove to be used other than with the canopy and as a separate unit, the canopy structure and support being a unit in itself. The relation of the canopy and stove allows the canopy to be raised as the chickens grow to accommodate chickens of different sizes while maintaining the proper relationship between the canopy and chickens which maintains better heating conditions. The raising of the canopy also provides a greater space between the stove and canopy for the circulation of air from around the stove and from within the brooding chamber under the canopy to heat the brooder-house and maintain better air conditions under the canopy.

I claim:

1. In a brooder, the combination with a heater, of a canopy associated with the heater, a bearing support connected with the canopy, a bearing-ring upon which said bearing support is movably mounted, a channel-bar support connected with the bearing ring and having a plurality of holes formed therein, a pin formed on the bearing ring in position to enter the holes in the channel-bar support for adjusting the ring thereon, guide-lugs formed on the bearing-ring and extending over the channel-bar support, and a base for supporting the heater and connected with the channel bar support independently thereof.

2. In a brooder, the combination with a heater, a supporting bar extending upwardly adjacent said heater and supported independently thereof, a bearing ring adjustably carried by said bar, and a canopy mounted on the bearing ring and having an opening therein.

3. In a brooder, the combination with a heater, a supporting bar extending upwardly beside said heater, a bearing ring adjustably carried by said bar, and a canopy journaled on the bearing ring and having an opening therein.

4. In a brooder, the combination of a heater for burning solid fuel, a canopy having an approximately central opening in the top thereof larger in area than the upper portion of the heater and within which is ar-

ranged the upper portion of the heater in spaced apart relation, providing a circulation of air through the top of the canopy from within the brooder chamber in any position in which the canopy may be adjusted, and an upright support for supporting the canopy in any adjusted position.

5. In a brooder, the combination of a heater, a base movable relative to the enclosure for the brooder, and on which the heater rests, a supporting device carried by the base and extending upwardly beside the heater, a canopy carried by the supporting device and having an opening in the upper portion thereof permitting a circulation of air from around the heater in approximately any adjusted position of the canopy, and means connecting the canopy with the supporting device and permitting vertical adjustment 15 and turning movement of the canopy relative to the heater.

6. A brooder comprising a heater, a base, a support carried by the base and extending upwardly beside the heater, and a canopy carried by said support and adjustable along the same, said canopy having an opening in the top substantially larger than the upper portion of the heater to permit adjustment to a position a substantial distance below the 25 top of the heater, and permitting circulation through the top of the canopy from around the heater.

7. A brooder comprising a heater, a base, a support carried by the base and extending 35 upwardly beside the heater, and a canopy carried by said support and adjustable along the same, said canopy having an opening in the top substantially larger than the upper portion of the heater to permit adjustment 40 to a position a substantial distance below the top of the heater, and permitting circulation through the top of the canopy from around the heater, said canopy having reinforcing means about said top opening, and having an 45 opening in a side thereof, and a journal for receiving said reinforcing means to support the canopy during turning thereof.

8. In a brooder, the combination of a heater, a supporting bar having a plurality 50 of holes formed therein, a bearing ring having a pin carried thereby in position to enter the holes for adjustably supporting the ring on the bar, guide lugs embracing the edges of the bar for limiting the relative positions 55 of the bearing ring and bar, a bearing support movably mounted on the bearing ring, and a canopy carried by said bearing support.

In testimony whereof I affix my signature.
60 ROBERT T. WILLIAMS.
